DESIGN FOR A HANDLE FOR SUITCASES OR SIMILAR ARTICLES

Leland George Stone, Fort Wayne, Ind., assignor
to The Magnavox Company, Fort Wayne, Ind.,
a corporation of Delaware

Application March 26, 1945, Serial No. 118,712

Term of patent 14 years

(Cl. D87—2)

To all whom it may concern:

Be it known that I, Leland George Stone, a citizen of the United States, residing at Fort Wayne, in the county of Allen, State of Indiana, have invented a new, original, and ornamental Design for Handle for Suitcases or Similar Articles, of which the following is a specification, reference being had to the accompanying drawing, forming part thereof.

In the drawing:

Figure 1 is a perspective view of my handle for suitcases or similar articles in its open position showing my new design; and

I claim:

The ornamental design for a handle for suitcases or similar articles, substantially as shown.

LELAND GEORGE STONE.
